CIRCUIT INTERRUPTER

John C. Ponstingl, Wilkinsburg, Pa., assignor to
Westinghouse Electric Corporation, East Pitts-
burgh, Pa., a corporation of Pennsylvania

Application March 29, 1945, Serial No. 585,461

10 Claims. (Cl. 200—87)

1 This invention relates to direct-current circuit interrupters and, more particularly, to arc-extinguishing structures therefor.

A general object of my invention is to provide an improved direct-current circuit interrupter which will more effectively extinguish the arc drawn therein than has heretofore been achieved.

Another object is to provide an improved blowout structure for a direct-current circuit interrupter.

The problem of arc blowout is encountered, when applying direct-current relays or other circuit interrupters for controlling such devices as magnetic motor-brakes, motor-field circuits, large contactor coils and various other devices, where the currents are of such magnitude to necessitate some type of arc blowout on the relays or interrupter contacts.

Present practice is to use relays having magnetic blowouts, where the energy for the blowout flux is supplied either by a shunt or series coil. Sometimes, relay contacts are shunted by a condenser of a suitable size to aid in extinguishing the arc.

The limiting factors relating to a shunt blowout coil scheme are that it is dependent on the circuit voltage, which may produce heat, thereby rendering possible the burning out of the coil, and it must have a suitable source for excitation.

One of the limiting factors of a series current type blowout scheme is that the blowout coil can only be designed to be effective over a certain current range. In other words, if the current to be interrupted is less than the minimum current for which the blowout coil was designed, the arc may not be extinguished when the switch contacts open to break the current circuit. This comes about because insufficient ampere turns exist in the magnetic circuit, and, as a consequence, insufficient magnetic "blowout" flux would be available for interruption of the arc.

The maximum operating current will be limited to the maximum heating permissible in the blowout coil. Furthermore, there is a continuous generation of heat in the blowout coil circuit.

The disadvantage of using a condenser shunting the arc is that the condenser may deteriorate with age and must be designed for a specific voltage and current. Since the condenser shunts the contacts, the problem of leakage is always present.

The purpose of my invention is to present a different form of magnetic blowout which has distinct advantages over the three present-day

schemes, as outlined above. This new method, in a sense, is "blowout" by induction.

Another object of my invention is to create magnetic flux in the blowout magnet of a direct-current circuit interrupter by inductively coupling the blowout magnet with the operating magnet for the interrupter.

Another object is to provide an improved blowout magnet structure in a direct-current circuit interrupter and to provide improved means for inductively setting up magnetic flux in the blowout magnet for effecting extinction of the arc drawn within the direct-current circuit interrupter.

15 Further objects and advantages will readily become apparent upon a reading of the following specification, taken in conjunction with the drawing, in which:

Figure 1 is a perspective somewhat diagrammatic view of a direct-current circuit interrupter embodying my invention and shown in the open-circuit position;

Fig. 2 is a plan view of a relay embodying my invention and shown in the open-circuit position;

Fig. 3 is a side elevational view of the relay shown in Fig. 2.

Referring to the drawing, and more particularly to Figure 1 thereof, the reference numeral 1 designates a panel upon which is mounted a direct-current relay or interrupter generally designated by the reference numeral 2. The blowout magnet 3 for the interrupter comprises a U-shaped magnet 4 secured by screws 5 to the panel 1 and inductively coupled to the operating magnet 6 of the interrupter by a copper strap 7. The movable armature 8 of the operating magnet 6 is pivotally mounted at 9 and is spring-biased to its open position by a tension spring 10.

40 A pigtail 11 is electrically connected to the movable armature 8 and hence to the movable contact 12, the latter making contacting engagement with the stationary contact 13 in the closed-circuit position. Preferably, a pigtail or lead 14 is connected to the stationary contact 13.

An operating coil 15 is wound about one leg 16 of the operating magnet 6 and serves, when energized, to set up magnetic flux in the operating magnet 6 to effect the closure of the movable armature 8 and hence to cause closure of the contacts 12, 13. Upon deenergization of the magnet 6, the spring 10 causes separation of contacts 12 and 13.

It will be apparent that, when the operating coil 15 is connected to a suitable source of direct-cur-

rent excitation, the magnetic flux will build up in the operating magnet 6, and the flux will die down upon opening of the circuit of coil 15. Both the building up and the dying down of the magnetic flux in the magnet 6 induces a current in the copper strap 7, the latter linking all of the lines of flux passing through the operating magnet 6. The induced current in the copper strap 7 in turn causes a building up of magnetic flux in the U-shaped magnet 4, to thereby set up a unidirectional magnetic field between the pole-pieces 17, 18 spaced laterally from the contact structure 12, 13.

From the foregoing, it will be apparent that, both during the opening and closing operations, there will be a change of flux in the operating magnet 6 and hence an induced current in the copper strap 7. Thus, during both the closing and opening operations, the induced current in the strap 7 will inductively cause a magnetic field to be created between the pole-pieces 17, 18 for blowing out the arc between contacts 12 and 13.

Figs. 2 and 3 show an application of the foregoing arrangement to a relay structure of conventional style, in which the operating magnet 6 comprises two legs 19, 20 and a bight portion 21. The operating coil 15 is disposed about the leg 20 and the copper strap 7 links the other leg 19. The operating magnet 6 is secured to the panel 1 by screws 22. The U-shaped magnet 4 is secured by screws 5 to the panel 1. The stationary contact 13 is supported by an insulating bar 23 secured by screws 24 to the opposed legs 25, 26 of the blowout magnet 3.

Integrally formed with the insulating bar 23 are two opposed plate portions 27, 28 which serve to confine the arc drawn between the stationary contact 13 and the movable contact 12. The movable contact 12 is mounted at the upper end of a movable armature 8, the latter being spring-biased to the open position by a tension spring 10. The armature 8 is pivoted about the pins 9, and a lead 11 makes electrical contact with a support 29 to which the armature 8 is pivoted at 9. Another lead 14 is electrically connected to the stationary contact 13.

The operation of the relay structure set forth in Figs. 2 and 3 is identical to that previously described, namely that a magnetic flux is inductively created between the pole-pieces 17, 18 across the contact structure 12, 13, during both the opening and closing operations, by virtue of the presence of the strap 7 which inductively links the blowout magnet 3 with the operating magnet 6.

Thus, during the transient period, when the relay operating coil is energized to close the relay contacts or deenergized to open the relay contacts, a current is induced in the copper loop 7. This sets up a magnetic flux in the blowout magnet and across the contact gap, to cause the arc, which is developed across the relay contacts 12, 13, to blow out.

Some of the advantages of arc blowout by induction are as follows: First, since a blowout coil in the usual sense is not required, there is, consequently, no necessity for replacing such a coil during the life of the interrupter. Also, since heat generation is reduced to a minimum, even replacement of the conducting strap 7 is not necessary. Secondly, as is evident from the drawing, the invention readily lends itself to a simple and economical construction. Thirdly, in utilizing my invention I am not limited to any particular current range which is necessary when

employing a series-current type blowout. Also my invention is not dependent on the voltage of the closing coil circuit inasmuch as there is no direct electrical connection interconnecting the conducting strap 7 and the closing coil 15. This is a distinct advantage over the shunt blowout scheme in which the voltage on the blowout coil circuit is directly dependent upon the operating voltage. Fourthly, it will be apparent from the foregoing description that the blowout circuit of my invention is energized only during the period when it is actually required, that is, during the initiation of both the opening and closing operations. Thus, there is a minimum of heat generated in the blowout coil circuit.

From the foregoing description of certain embodiments of my invention, it will be apparent that some advantages of the disclosed method of setting up a blowout field are that the blowout action is obtained only at the time of interruption, or during closing during sparkover when such blowout action is desired, and that the induction method applied eliminates parts and renders the resulting arrangement exceedingly simplified.

Although I have shown and described specific structures, it is to be clearly understood that the same were merely for the purpose of illustration and that changes and modifications may readily be made therein by those skilled in the art, without departing from the spirit and scope of the appended claims.

I claim as my invention:

1. In a direct-current circuit interrupter, separable contacts to establish an arc, operating means for the contacts including an operating magnet having two legs, a blowout magnet having two legs for extinguishing the arc, and conducting strap means coupling one leg of the operating magnet with one leg of the blowout magnet.
2. In a direct-current circuit interrupter, separable contacts to establish an arc, operating means for the contacts including an operating magnet having two legs, a conducting strap encircling one leg, a blowout magnet having two legs to extinguish the arc, and the conducting strap also encircling a leg of the blowout magnet to couple the two magnets together.
3. In a direct-current circuit interrupter, separable contact means for establishing an arc, operating means for causing the separation of the separable contact means including an operating magnet, an operating coil for setting up magnetic flux in the operating magnet, a magnetic blowout structure for assisting in the extinction of the arc, and a current conducting loop circuit linking the operating magnet with the magnetic blowout structure to induce magnetic flux in the latter upon a change of magnetic flux in the operating magnet.
4. In a direct-current circuit interrupter, a relatively stationary contact, a movable contact separable from the stationary contact to establish an arc, an operating magnet including a movable armature carrying the movable contact, an operating coil for setting up magnetic flux in the operating magnet to thereby cause closure of the contacts, a magnetic blowout structure for assisting in the extinction of the arc, and a current conducting loop circuit linking the operating magnet with the magnetic blowout structure to induce magnetic flux in the latter upon a change of magnetic flux in the operating magnet.
5. In a direct-current circuit interrupter, sep-

arable contact means for establishing an arc, operating means for causing the separation of the separable contact means including an operating magnet, an operating coil for setting up magnetic flux in the operating magnet, a blowout magnet for assisting in the extinction of the arc, and current conducting means coupling the operating magnet with the blowout magnet to induce magnetic flux in the blowout magnet upon a change of magnetic flux in the operating magnet.

6. In a direct-current circuit interrupter, a relatively stationary contact, a movable contact separable from the stationary contact to establish an arc, an operating magnet including a movable armature carrying the movable contact, an operating coil for setting up magnetic flux in the operating magnet to thereby cause closure of the contacts, a blowout magnet for assisting in the extinction of the arc, and current conducting means coupling the operating magnet with the blowout magnet to induce magnetic flux in the blowout magnet upon a change of magnetic flux in the operating magnet.

7. A direct-current circuit interrupter including separable contact means for establishing an arc, operating means for causing the separation of the separable contact means including an operating magnet, an operating coil for setting up magnetic flux in the operating magnet, the operating magnet being energized during each closing operation of the circuit interrupter and being deenergized during each opening operation of the circuit interrupter, a magnetic blowout structure for assisting in the extinction of the arc, and a current conducting loop circuit linking the operating magnet with the magnetic blowout structure so that during the energization and deenergization of the operating magnet magnetic blowout flux may be inductively generated in the magnetic blowout structure.

8. A direct-current circuit interrupter including a relatively stationary contact, a movable contact separable from the stationary contact to establish an arc, an operating magnet including a movable armature carrying the movable contact, an operating coil for setting up magnetic flux in the operating magnet to thereby cause closure of the contacts, the operating magnet being energized during each closing operation of the circuit interrupter and being deenergized during each opening operation of the circuit interrupter, a magnetic blowout structure for assisting in the extinction of the arc, and a current

conducting loop circuit linking the operating magnet with the magnetic blowout structure so that during the energization and deenergization of the operating magnet magnetic blowout flux may be inductively generated in the magnetic blowout structure.

9. A direct-current circuit interrupter including separable contact means for establishing an arc, operating means for causing the separation of the separable contact means including an operating magnet, an operating coil for setting up magnetic flux in the operating magnet, the operating magnet being energized during each closing operation of the circuit interrupter and being deenergized during each opening operation of the circuit interrupter, a blowout magnet for assisting in the extinction of the arc, and current conducting means coupling the operating magnet with the blowout magnet so that during the energization and deenergization of the operating magnet magnetic blowout flux may be inductively generated in the blowout magnet.

10. A direct-current circuit interrupter including a relatively stationary contact, a movable contact separable from the stationary contact to establish an arc, an operating magnet including a movable armature carrying the movable contact, an operating coil for setting up magnetic flux in the operating magnet to thereby cause closure of the contacts, the operating magnet being energized during each closing operation of the circuit interrupter and being deenergized during each opening operation of the circuit interrupter, a blowout magnet for assisting in the extinction of the arc, and current conducting means coupling the operating magnet with the blowout magnet so that during the energization and deenergization of the operating magnet magnetic blowout flux may be inductively generated in the blowout magnet.
